SHOE POLISHING MACHINE OR THE LIKE

Joseph W. Jones, New York, N. Y.

Application June 17, 1949, Serial No. 3,361

Term of patent 14 years

(Cl. D9—2)

To all whom it may concern:

Be it known that I, Joseph W. Jones, a citizen of the United States, residing at New York, in the county and State of New York, have invented a new, original, and ornamental Design for a Shoe Polishing Machine or the like, of which the following is a specification, reference being had to the accompanying drawing, forming part thereof.

Fig. 1 is a front perspective view of a shoe polishing machine or the like embodying my new design; and

Fig. 2 is a rear perspective view of the same.

The dominant features of my design reside in those portions shown in full lines.

I claim:

The ornamental design for a shoe polishing machine or the like, substantially as shown and described.

JOSEPH W. JONES.
